(57) **CLAIM**

I claim the ornamental design for a fluted handle, as shown and described.

DESCRIPTION

FIG. 1 is a front perspective view of a fluted handle showing my new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a bottom plan view of FIG. 1; and,

FIG. 8 is a cross-sectional view taken along line 8-8 of FIG. 2.
